UNITED STATES PATENT OFFICE.

EDSON A. MILLER, OF EAST PALESTINE, OHIO, ASSIGNOR TO EAST PALESTINE RUBBER COMPANY, OF EAST PALESTINE, OHIO, A CORPORATION OF OHIO.

DESIGN FOR A TIRE-CASING.

47,265.

Specification for Design.

Patented Apr. 27, 1915.

Application filed December 28, 1914. Serial No. 879,404. Term of patent 7 years.

To all whom it may concern:

Be it known that I, EDSON A. MILLER, a citizen of the United States, residing in the village of East Palestine, county of Columbiana, and State of Ohio, have invented a new, original, and ornamental Design for Tire-Casings, of which the following is a specification, reference being had to the accompanying drawing, forming part thereof.

The figure is a plan view of a portion of a tire casing, showing my new design.

I claim:—

The ornamental design for a tire casing, as shown.

EDSON A. MILLER.
